CENTERING DEVICE FOR CONDUCTING LIQUEFIED ARC-EXTINGUISHING GAS TO A HIGH-PRESSURE RESERVOIR

Claus Kessler, Berlin-Dahlem, Germany, assignor to Siemens-Schuckertwerke Aktiengesellschaft, Erlangen, Germany, a corporation of Germany
Filed Mar. 31, 1965, Ser. No. 444,189
2 Claims. (Cl. 200—148)

This invention relates generally to circuit-interrupting structures utilizing an arc-extinguishing gas, and more particularly, to an improved centering device for centering the flow of liquefied gas, under low ambient temperature conditions, through the high-pressure gas-conducting tube to the grounded high-pressure gas-reservoir chamber.

A general object of the present invention is to provide an improved liquefied-gas centering device to prevent the deposition of conducting particles on the inner side walls of the high-pressure gas supply tube. There may be two kinds of contaminants, one consisting of metallic flakes, or cuttings from castings which must be machined, and are not fully washed away by shop procedures. Secondly, if the drying of the sulfur-hexafluoride (SF_6) gas is not kept under control, an excess of moisture in the top high-pressure reservoir will condense as water droplets and with a resultant chemical reaction with the SF_6 gas will lead to conducting water droplets.

Another object of the invention is the provision of an improved liquefied-gas return device to prevent the hazard of flashover along the insulating high-pressure gas supply tube, by providing a centering device, including a centering trough, which will guide any liquefied gas to the centerline of the high-pressure gas supply tube and thereby prevent the deposition of conducting particles along the inner side walls of the insulating high-pressure gas supply tube.

Some high-voltage power circuit breakers using sulfur-hexafluoride (SF_6) gas as an interrupting medium have had the hazard of electrical failures of the high-pressure gas-supply line from the high-pressure gas-reservoir chamber at ground potential to the high-pressure gas-reservoir chamber at line or high potential. These high-pressure gas supply lines are made of insulating tubing and are subjected to relatively high electrical stresses. Such a high-pressure gas supply line conducts gas from the high-pressure gas reservoir chamber at ground potential to the high-pressure gas reservoir chamber at high or line potential, and returns liquid condensate to ground potential, where it is revaporized by suitable auxiliary heating equipment. The exact cause of such failures of such high-pressure gas supply tubes has not been determined, but it is suspected that the condensate in the reservoir at high potential may pick up conducting particles, and that while flowing down the high-pressure gas-supply tube may deposit some of these conducting particles on the inside wall of the gas supply tube. Traces of such deposits have been found on some high-pressure gas supply tubes. This condition is probably of most importance in the vicinity of the high-potential parts, where the voltage gradient along the high-pressure supply tube has the highest value.

It is, accordingly, an object of the present invention to prevent the deposition of the liquid condensate which may carry such conducting particles on the inner side walls of the high-pressure gas supply tube to prevent the resultant hazard of voltage flashover along the axial length of the supply tube.

Further objects and advantages will readily become apparent upon reading the following specification, taken in conjunction with the drawings, in which:

2

FIGURE 1 is a side elevational view of one pole of a three-pole high-voltage gas-type circuit-interrupting structure embodying the principles of the present invention; and,

FIGS. 2 and 3 collectively show a composite vertical sectional view taken substantially along the line II—II of FIG. 1, the upper figure portion FIG. 2 indicating the gas-flow conditions into the rotatable interrupting arm during interrupting conditions, and the lower figure portion FIG. 3 indicating the closed position of the main blast valve in the closed-circuit position of the interrupter.

Referring to the drawings, and more particularly to FIG. 1 thereof, the reference numeral 1 designates a three-pole gas-blast type of high-voltage circuit interrupter suitable for high voltages, say 500 kv. or 700 kv. As is well known by those skilled in the art, for the higher voltages it is merely necessary to incorporate additional interrupting heads 2 serially into the circuit to withstand the high voltage in the open-circuit position of the device.

As illustrated in FIG. 1, the interrupting heads 2 are supported at the upper ends of upstanding insulating columns 3, the lower ends of which are supported upon a horizontally-extending base framework 4. As shown, the base framework 4 comprises a plurality of heavy structural steel members 5-7 supporting a longitudinally-extending high-pressure gas reservoir tank 10 of sulfur hexafluoride (SF_6) gas and suitable compressor equipment 12. Insulating angle supports 15 may additionally be provided to enable the interrupting heads 2, which are of relatively heavy metal, to withstand wind-loading forces.

A current-transformer structure 19 is supplied in series with the line circuit L_1 , L_2 to effect a measurement of the current flow through the interrupter 1. Although FIG. 1 merely shows a side elevational view of one pole-unit A only, it is to be understood that normally there are three such pole-units in side-by-side relation to enable the control of a three-phase transmission circuit.

As more fully set forth in detail in U.S. patent application filed June 12, 1964, Ser. No. 374,708, (W.E. 34,561) by Roswell C. Van Sickle, entitled "Interrupting Structures and Operating Mechanisms for Compressed-Gas Circuit Interrupters," and assigned to the Westinghouse Electric Corporation, disposed within each of the interrupting heads 2 is a rotatable interrupting arm 25 carrying a pair of serially-related interrupting units 26 at the opposite free ends thereof. The interrupting arm 25 is hollow, as at 25a, and permits the transmission therethrough of a blast of high-pressure gas from a high-pressure gas-reservoir chamber 27 through a horizontally-movable blast valve 30, which is actuated to the open and closed positions by suitable blast-valve operating mechanisms, generally designated by the reference numeral 32, and illustrated in detail in the aforesaid patent application.

During the opening operation the rotatable interrupting arm 25 causes the separation of two movable contacts 34 from stationary contact structures, not shown, which are disposed at the interior ends of terminal bushings 36, which extend laterally into the interior of the interrupting heads 2. Thus, in the closed-circuit position of the device, the two serially-related movable contacts 34, which are provided at opposite extremities of the rotating interrupting arm 25, make contacting engagement with the stationary contact structures, not shown, which are disposed at the fixed interior ends of the terminal bushings 36 within the interior 40 of the interrupting heads 2.

Simultaneously with the rotative opening movement of the interrupting arm 25, there is effected an opening of the blast-valve mechanism 32 to effect inward opening movement of the blast-valve structure 30 and consequently an outward flow of high-pressure gas, as indicated by

the arrows 33 in FIG. 2. In the closed-circuit position of the interrupter, and in the fully opened-circuit position of the interrupter, the blast-valve 30 is maintained in an outward closed position, as shown in FIG. 3. In this position of the blast-valve 30, the gas flow is halted, and, as is customary, during the closing operation of the interrupter, the blast-valve 30 is likewise maintained in the closed-circuit position.

In a gas-type circuit interrupter using certain gases, such as sulfur hexafluoride (SF₆) gas, during low-temperature ambient conditions, there is the distinct possibility of liquefaction of the high-pressure SF₆ gas disposed within the high-pressure high-voltage reservoir chamber 27. Such liquefied SF₆ gas, or liquid condensate may run downwardly by gravity flow along the high-pressure gas supply tube 50 to the lower grounded high-pressure reservoir chamber 10. As pointed out above, there is the possibility that the liquid SF₆ condensate will pick up conducting particles in the chamber 27 and cause them to be deposited along the inner side walls of the insulating high-pressure gas supply tube 50. If this continues, there results the distinct hazard of voltage flashover axially along the insulating high-pressure tube 50. It is, accordingly, an object of the present invention to avoid the possibility of such deposition by centering the downward flow of the liquefied SF₆ condensate. This will avoid the cumulative deposition of conducting particles along the inside walls of the insulating high-pressure supply tube 50 and will consequently avoid such hazard of voltage flashover. As shown in FIG. 3, it will be noted that there is provided a 90° elbow 60, which may form a part of a casting 61, which interconnects the upper end of the high-pressure supply tube 50 with the high-pressure high-voltage reservoir 27. As a result, any liquid SF₆ condensate, which accumulates within a recess portion 70 of the casting 27, will be centered by causing it to flow through a trough, or grooved portion 72 of the elbow connection 60 to fall vertically downwardly through the center of the insulating high-pressure tube 50, as indicated by the liquid droplets 80. These liquefied droplets 80, in avoiding contact with the inner walls 50a of the high-pressure supply tube 50, will drop down into the grounded high-pressure horizontally-extending tank 10.

Although not particularly visible in FIG. 1 of the drawings, in fact the longitudinally-extending high-pressure gas-supply reservoir 10 at ground potential is tipped slightly, so that one end 10a thereof is at a lower level than the other end. As a result, any condensate 80 which falls downwardly into the high-pressure grounded reservoir chamber 10 will flow to one end 10a thereof, and will be vaporized by a heater 84, which is disposed internally of the high-pressure reservoir 10 and is connected, through a thermostat 86, to a suitable electrical supply circuit 88. Suitable insulation 90 is provided around the tank 10 and around an upstanding bellows portion 92 thereof to prevent the application of low-ambient temperatures from causing a liquefaction of the high-pressure SF₆ gas provided in the lower chamber 10.

The thermostat 86 will cause an energizing of the heater 84 under certain temperature conditions, which will result in a vaporization of any condensate 80, which is collected at the lower end of the tank 10.

Although the present invention has been described in connection with sulfur hexafluoride (SF₆) gas, it is to be clearly understood that the same structure could be provided for other arc-extinguishing gases, which are susceptible of liquefaction under low-ambient temperature operating conditions.

The upstanding column 3 serves as a means of transmitting relatively low-pressure gas within the region 40 downwardly and through a connection 99 into a compressor 100, which may be responsive to certain differential density instruments 102, so that when the pressure builds up too much within the region 40, or similarly, if the high pressure within the reservoirs 10, 27 drops too low, the compressor 100 will be started up and thereby effect a compression of high-pressure SF₆ gas into the high-pressure reservoirs 10, 27.

Although there has been illustrated and described a specific structure, it is to be clearly understood that the same was merely for the purpose of illustration, and that changes and modifications may readily be made therein by those skilled in the art, without departing from the spirit and scope of the invention.

I claim as my invention:

1. In a high-voltage compressed-gas type of circuit interrupter having separable contacts and means utilizing a high-pressure blast of gas to effect extinction of the arc established at said contacts, said interrupter further having a high-voltage high-pressure gas-reservoir chamber and a grounded high-pressure gas reservoir chamber with an interconnecting high-pressure insulating supply tube therebetween, the combination therewith of a centering-trough means for centering the flow of liquid condensate under low-ambient temperature conditions through said high-pressure insulating supply tube, whereby the deposition of entrained conducting particles in the condensate on the inner side walls of the insulating supply tube will be avoided, and thereby the hazard of voltage flashover eliminated.

2. The combination according to claim 1, wherein the centering-trough means comprises a 90° elbow connection of metal attached to the high-voltage high-pressure gas-reservoir chamber.
